UNITED STATES PATENT OFFICE

JOSEPH DYSON SCAIFE, OF NOTTINGHAMSHIRE, ENGLAND, ASSIGNOR TO THE HEALD MACHINE COMPANY, OF WORCESTER, MASSACHUSETTS, A CORPORATION OF MASSACHUSETTS

GRINDING MACHINE

Application filed January 16, 1929, Serial No. 332,859, and in Great Britain December 19, 1928.

The present invention relates to grinding machines, particularly to that type known as oscillating raceway grinding machines. In such machines the work piece is continuously rotated upon its own axis and is at the same time swung or oscillated through an arc of a circle about an axis which—in the case of a ball race—is arranged to be tangential to the locus of the centre of curvature of radial sections of the raceway to be ground and is perpendicular to the plane of contact between wheel and work piece which contains the center of the wheel; whilst the grinding wheel itself is rapidly rotated upon its axis and is so mounted as to be capable of being moved into and out of engagement with the work piece to effect grinding thereof.

In such machines the grinding wheel is usually fed in cutting relation to the work piece manually or by a cam arrangement. In the former case it is extremely difficult to produce an entirely accurately ground work piece, and in the latter case it is necessary to pre-form a suitable cam, and this is by no means a simple matter. Moreover even should the cam be accurately made to produce the desired effect its contour will almost certainly vary during use.

The chief object of the present invention therefore is to provide a machine of this kind in which the grinding wheel or the like is positively fed in cutting relation to the work piece in an improved manner.

A further object of the present invention is to provide a grinding machine of the kind referred to, in which successive work pieces ground with great precision may be produced without replacement of the grinding wheel, and without the inconvenience incidental to renewing the grinding wheel and resetting the machine for each work piece to be ground.

A further object of the present invention is to provide a grinding machine of the kind referred to in which a predetermined relative movement may be imparted between the work piece and the grinding wheel to compensate for wear or the like on the grinding wheel.

Another object of the present invention is to provide a grinding machine of the kind referred to in which the reduction of the grinding wheel from wear or the like, incidental to a grinding operation, is compensated for automatically.

A still further object of the invention is to provide means for truing the grinding wheel after each grinding operation, such means being preferably brought into operation automatically during setting up of a fresh work piece in the machine.

In order that the invention may be more clearly understood and readily carried into effect reference may now be had to the accompanying drawings, which illustrate the invention by way of example, and in which:

Fig. 1 is a front elevation of a grinding machine constructed according to the invention, part of the base of the machine being broken away in order to more clearly show the operation of certain mechanism, and the truing mechanism being omitted from this view.

Fig. 2 is a plan view of the machine.

Fig. 3 is a fragmentary rear elevation on an enlarged scale, showing the mechanism for bringing the truing device into truing position.

Fig. 4 is a fragmentary elevation of the truing mechanism as seen from the left hand end of the machine, the parts being shown on the same scale as Fig. 3.

Fig. 5 is an isometric view of the actuating mechanism for moving the wheel in cutting relation to the work, these parts being shown as detached from the machine.

Fig. 6 is a sectional view taken on the line 6—6 of Fig. 1.

Like reference characters refer to like parts throughout the drawings.

Referring first to Figures 1, 2, and 6 of the accompanying drawings, the reference numeral 1 indicates the work head or head stock. The head 1 provides journals for a horizontally disposed rotatable shaft 2. The head is carried by a platform 3 adapted for oscillatory movement about a vertical axis 4. For this purpose the platform 3 has a shaft 5 associated therewith either integrally or otherwise, said shaft being rotatably mounted in suitable bearings such as ball bearings.

95

100

6 mounted on the machine frame. Suitable slides 7 and 8, preferably disposed at right angles to one another, are provided upon the platform 3, so as to permit the horizontally disposed shaft 2 to be moved into any desired position. The shaft 2 is provided at one end with a face plate 9 to which the work piece may be secured in any desired manner, and also has a pulley 10 mounted thereon to accommodate a driving belt, not shown, whereby the shaft may be rotated.

At the right hand side of the machine as viewed in Figures 1 and 2 is a slide or carrier 11, which is mounted upon the machine frame 15 or bed in such a manner that it is adapted to be moved in a horizontal plane longitudinally of the machine towards and away from the head 1. For this purpose the carrier 11 may be provided with suitable guiding means between itself and the machine frame, and also with a rack 12 co-operating with a gear 13 suitably mounted upon the machine frame, the gear being adapted to be rotated by means, for example, of the handle 14 and attached pinion 14' to cause movement of the carrier 11 with respect to the frame.

Various elements and mechanisms are mounted upon the carrier 11 and these will now be described in detail. Firstly there is 30 a slide 15 adapted for movement transversely of the machine frame. Referring to Figs. 1, 2 and 5 movement may be imparted to the slide 15 by a connecting rod 16 which is pivotally connected to a portion 17 provided by 35 the slide at one end 18, and which is pivotally connected at its other end to an element 20a.

Referring now to Figs. 2 and 5, the driving mechanism for the element 20a which is 40 shown as a disc, is generally designated by the numeral 19. The element 20a is adapted to be rotated manually from a handle 21 associated with a hand wheel 21a, or by power from a pair of stepped pulleys 22a and 22b, 45 the former of which is driven at a constant speed from any suitable source of power. By selecting appropriate opposite grooves in the stepped pulleys 22a and 22b for a connecting belt, not shown, various speeds may be imparted to a shaft 19a which is detachably secured to the pulley 22b by means of a clutch 22c. The shaft 19a has a worm 19b fastened thereto which drives a worm wheel 19c, and the latter is fastened to a shaft 19d and provides also a worm 19e, which is in mesh with a large worm wheel 19f that is mounted on the same shaft 19g as the element 20a. Likewise fastened to the shaft 19g is a worm wheel 21b which is in mesh with a worm 21c on 55 a shaft 21d to which is fastened the hand wheel 21a. The worms 19b, 19e and 21c are of steep pitch so that they will either drive the various worm wheels with which they are in mesh, or be driven therefrom.

65 The connection 20 between the element

20a and the connecting rod 16 is eccentric to the axis of revolution of the element 20a, which axis is the same as the axis of the shaft 19g. Thus in effect this connection 20 is a crank, the throw of which determines the 70 movement of the slide 15 as the element 20a is rotated.

Upon the slide 15 and also adapted for movement transversely of the machine with respect to the slide 15 is mounted a slide 23 which carries a suitable journal 24 for a horizontally disposed grinding wheel shaft 25 which is adapted to be rapidly rotated in any convenient manner for example by means of belting applied to the pulley 25a.

At one end the slide 23 has associated therewith mechanism—shown in Figs. 1 and 2—by means of which it may be moved transversely of the machine frame relatively to the slide 15. This mechanism may comprise a ratchet wheel 26 mounted upon a shaft 27 journaled in an element 28 attached to the slide 23, said shaft being provided with a screw thread adapted to mesh with a co-operating nut element 29 associated with the slide 15 in such a manner that rotation of the shaft 27 causes corresponding movement of the slide 23. A finger 30 is mounted upon an arm 31 rockably mounted upon the shaft 27 and is adapted to co-operate with an inclined surface or cam 32 mounted upon the machine frame during movement of the carrier 11 longitudinally of the machine. The arm 31 also carries a pawl or pawls 33 adapted to co-operate with the teeth of the ratchet wheel 26 to cause rotation thereof, and consequently of the shaft 27, to move the slide 23 with respect to the slide 15 as and for a purpose which will be explained hereinafter.

According to the invention the improved machine is provided with mechanism for truing the peripheral surface of the grinding wheel or the like while a fresh workpiece is being set up in the machine, and this mechanism may if desired be brought into and thrown out of operation automatically during movement of the carrier longitudinally of the machine. I will now proceed to describe one form of truing device which may be used but it is to be understood that any other suitable device may be employed.

As shown in Figs. 3 and 4 a pin or projection 34 is attached to the machine frame at the rear thereof with it a pair of arms 35 of a bell crank lever 36, pivotally mounted at 37 upon the carrier 11, co-operate. The end of the bell crank lever 36 opposite the arms 35 (which are in parallel relation) is connected by means of a rod 39 to an arm 40, the connections 38 and 38a being universal joints. The arm 40 is attached to a support or arm 43 for a diamond or like truing device 44, all these parts being journaled at 41 in a standard 42 carried by the slide or carrier 11. It

will thus be seen that movement of the outer end of arm 40 causes corresponding movement of the outer end of arm 43 of the truing device 44, to swing the truing device 44 up and down about the axis 41.

The truing device 44 is mounted in a suitable holder 45 which is journalled in a bearing portion 46 provided by the arm 43, so that the truing device 44 may be oscillated. That portion of the holder 45 which contains the diamond or other truing device is offset from the axis of oscillation of the holder, so that the point of the diamond may face the center of oscillation. In order to oscillate the holder 45 about its axis 47, the arm 43 supports a suitable prime mover, such as a Pelton water motor 48. Upon the shaft 49 of the Pelton motor 48 is a worm 50, which meshes with a worm wheel 51 that is rotatably mounted upon an extension of the arm 43. Attached to the top of the worm wheel 51 is a pin 52, and a link or arm 53 connects this pin to a pin or lug 54 provided by the holder 45. Rotation of the wheel 51 therefore causes oscillation of the holder 45 about the axis 47. The water or other elastic fluid for the Pelton wheel 48 is supplied by means of a flexible pipe 55 and a valve 56 for the water is operated in any convenient manner which may be automatic if desired to ensure that fluid is supplied thereto only at the requisite times.

For the purpose of imparting oscillatory movement to the headstock 1 the vertical shaft 5 has fastened thereto a suitable arm 5a, shown in Fig. 2 as extending from a split collar 5b, and the arm 5a is connected by means of a link rod 57 with a crank or the like 58 which is mounted on the top of a shaft 58a. Shaft 58a is suitably journalled in the machine and received inside of a sleeve 58b. See Fig. 1. On the bottom of the shaft 58a is keyed a movable collar 58c, the top portion of which consists of a clutch element for engagement with corresponding clutch teeth provided by the sleeve 58b. Fastened to the sleeve 58b and surrounding it is a worm wheel 58d which meshes with a worm 59a on the end of a shaft 59. The outer end of the shaft 59 is supported by a bearing bracket 60 depending from the side of the machine frame, and stepped pulleys 61 are fastened to said shaft adjacent the bracket 60. By means of the pulleys 61 and oppositely arranged stepped pulleys 62 and a drive pulley 64, the last two being located on a countershaft 63, the shaft 59 may be driven at any desired speed.

A handle 65 and a crank or the like are provided to raise and lower a connector 65a, the lower end of which is pivotally attached to a lever 65b which operates the clutch collar 58c. In this manner the shaft 58a can be stopped and started, thus to control oscillation of the shaft 5 and the head 1.

Having described the principal parts of the improved machine necessary for an un-

derstanding of my invention I will now proceed to describe the manner of operation during grinding of a series of ball raceways.

In setting up the machine the workpiece is secured in a chuck, not shown, attached to the face plate 9 in any appropriate manner, and the shaft 2 is then adjusted by means of the slides 7 and 8 until the axis 4 of the vertical shaft 5 is tangential to the locus of the centre of curvature of the raceway to be ground. The slides 7 and 8 are then secured in their adjusted positions. During this operation the headstock is stationary, the clutches in the driving means for the shaft 5 and also for the shaft 2 being at this time disengaged.

Assuming a grinding wheel 66 to have been mounted upon the shaft 25, the clutches are now engaged thus imparting to the workpiece oscillation about the axis 4 and rotation about the axis 2 and the operator rotates the handle 14 which has the effect of moving the carrier 11 and consequently the grinding wheel 66 mounted upon the shaft 25 longitudinally of the machine towards the workpiece. During this forward movement of the slide the fluid supply of the Pelton wheel is automatically cut off and the arms 35 of the bell crank lever 36 contact with the pin 34 on the frame. The bell crank lever 36 is therefore rocked upon its pivot 37 and through the connection 39 a downward movement is imparted to the free end of the arm 40 which causes the outer end of arm 43 to swing upwardly about the pivot 41 to raise the truing device 44 and associated parts to an inoperative position.

The longitudinal movement of the carrier 11 is continued until the plane passing through the center of the grinding wheel and perpendicular to the axis contains the vertical axis 4 the carrier being stopped in this position by suitable stops thereon engaging co-operating stops on the frame of the machine. These stops are of course adapted to be adjusted according to the size of grinding wheel and workpieces set up in the machine.

The handle 21 is now manually operated to cause the slide 15 and the elements and mechanism associated therewith or carried thereby to be moved transversely of the machine through the crank motion and connecting rod 16; this movement continuing until the grinding wheel just engages the work. At this point the clutch 22c in the driving mechanism 19 of the slide 15 is engaged and the slide 15 is driven by power until the grinding operation has been completed, when the clutch 22c is disengaged and the grinding wheel withdrawn clear of the work by manipulation of the handle 21. It will be understood that during the whole time of engagement between the workpiece and the grinding wheel the former is being oscillated continuously about the axis 4 through the

driving connections previously described. The throw of the crank motion in the drive of the slide 15 determines of course the travel of the slide 15 and consequently the maximum diameter of the raceway being ground.

5 As soon as the actual grinding operation has been completed, oscillation of the shaft 5 is stopped by manipulation of the handle 65, and the carrier 11 is moved longitudinally 10 of the machine to withdraw the grinding wheel out of the work piece by manipulation of the handle 14.

During this movement of the carrier 11 the finger 30 rides up the inclined surface or 15 cam 32 to rock the arm 31 and consequently the pawl or pawls 33 upwardly. The effect of this is to rotate the ratchet wheel 26 and shaft 27 causing movement of the slide 23 transversely of the machine and relatively to 20 the slide 15. This movement is calculated to be equivalent to that required to compensate for the wear on the grinding wheel during the preceding grinding operation and in the machine shown is sufficient also to permit an 25 amount of material to be removed from the grinding wheel by the truing device 44.

The truing device 44 is brought into operation during the movement of the carrier 11 away from the head 1 by the arms 35 of the 30 bell crank lever 36 moving out of contact with the projection 34 on the frame of the machine. It should be noted at this point that the arm 43, the Pelton wheel 48, oscillating member 45 and the other parts of the truing mechanism, including the arm 40, are raised by the movement of the carrier 11 to carry the grinding wheel to grinding position, so that their combined center of gravity has moved beyond the vertical plane of the pivotal axis 41. 35 Thus the weight of these parts, during the grinding operation, does not tend to move the carrier 11 to carry the wheel 66 out of grinding position, but rather tends to hold it there against the stops before mentioned. 40 The subsequent movement of the carrier 11 to carry the wheel out of position after a grinding operation causes positive movement of the truing mechanism in a clockwise direction, Fig. 4, by reason of the fact that the 45 pin 34 fits between the arms 35, 35. The provision of these two arms also insures the movement of the truing mechanism without shock, and permits it to be lowered to the position shown in Fig. 4, where it rests against 50 stops, not shown. At the same time the operation of the prime mover for oscillating the diamond truer, in this case the Pelton wheel 48, is initiated with the result that the diamond holder 45 is oscillated about its 55 axis 47 through the connections and in the manner already described to true the grinding wheel. The truing operation serves to maintain the cutting side of the grinding wheel at the moment of greatest advance of 60 the slide 23, tangent to a fixed vertical plane 65

that is parallel to the motion of the carrier 11, by reason of the fact that the whole truing mechanism is carried by the carrier 11 and slide 23 and is always oscillated about the same axis 47. The compensating mechanism 70 shown in Fig. 1 and already described which causes a slight movement of the slide 23 on the slide 15 after each grinding operation serves to advance the grinding wheel towards the dressing device 44 by small increments for each grinding operation to insure contact 75 between them. As the grinding wheel is always brought to the same position laterally of the machine by the connecting rod 16 and the actuating mechanism 19, uniform size of successive workpieces is insured.

During the truing operation the previously 80 ground workpiece is removed from the machine and a new one substituted therefor, the operation of the machine as already described 85 being then repeated.

Owing to the fact that the slide is positively moved to effect grinding by means of a crank motion, a coarse feed is provided at the commencement of the grinding operation, 90 and the feed is reduced gradually during the grinding operation until at maximum stroke of the crank it is zero, thereby enabling a very smooth finish to be obtained upon the workpiece.

95 Although in the foregoing I have described but one particular embodiment of my invention it is to be understood that many variations may be made therein without departing from the spirit and scope of the invention as defined in the accompanying claims.

In order to insure correct action of the machine and to procure precision despite possible lost motion in some of the connections operating the slide 15, means is provided to urge the slide in one direction or the other to take up any such lost motion. This means is shown in Fig. 3 and comprises a shaft 71 which is given a torque by means of a spring 72, an arm 73 being fastened to the end of the shaft 71, and the upper end of said arm being attached by a pin and fork connection 74 to the slide 15.

What I claim is:—

1. A grinding machine of the kind described comprising a headstock for a workpiece, a rotatable shaft for a grinding wheel, means for moving said shaft endwise, to dispose said wheel in grinding position and a crank motion for moving said shaft transversely to said endwise movement to bring said grinding wheel into and out of grinding engagement with said workpiece.

2. A grinding machine of the kind described comprising a headstock for a workpiece, a rotatable shaft for a grinding wheel, means for moving said shaft endwise to dispose said wheel in grinding position, a crank motion for moving said shaft transversely to said endwise movement to bring said grind-

- ing wheel into and out of grinding engagement with said workpiece, means for dressing said wheel, and means for compensating for wear on the grinding wheel and its reduction 5 in diameter by dressing.

3. A grinding machine of the kind described comprising a headstock for a workpiece, a rotatable shaft for a grinding wheel, means for moving said shaft endwise to dis- 10 pose said wheel in grinding position, a crank motion for moving said shaft transversely to said endwise movement to bring said grinding wheel into and out of grinding engagement with said workpiece, means for dressing said wheel, and means for automatically im- 15 parting a predetermined relative movement between said shaft and said headstock to compensate for wear of the grinding wheel and its reduction in diameter by dressing.

4. A grinding machine of the kind de- 20 scribed comprising a headstock for a work- piece, a rotatable shaft for a grinding wheel, means for moving said shaft endwise to dis- pose said wheel in grinding position, a crank motion for moving said shaft transversely to 25 said endwise movement to bring said grinding wheel into grinding engagement with said workpiece, means brought into operation by 30 said endwise movement in one direction for truing the peripheral surface of said wheel, and means for imparting a predetermined transverse movement to said shaft to com- 35 pensate for wear of the grinding wheel and its reduction in diameter by dressing.

5. A grinding machine of the kind de- 40 scribed comprising an oscillatory headstock for a workpiece, a slide, a second slide mounted upon said first mentioned slide, a rotatable shaft for a grinding wheel mounted upon 45 said second mentioned slide, means for mov- 50 ing said slides longitudinally of the machine to dispose said wheel in grinding position, a crank motion for simultaneously moving said slides transversely to bring the grinding wheel into engagement with the workpiece, means for dressing said wheel, and means for moving one of said slides independently of the other to compensate for wear on the grinding wheel and its reduction in diameter by dressing.

6. A grinding machine comprising a head- 55 stock capable of oscillation about a vertical axis, a horizontally disposed rotatable shaft for a workpiece mounted upon said head- 60 stock, a horizontally disposed rotatable grinding wheel shaft, a slide capable of movement in a horizontal plane transversely of said machine and carrying said grinding wheel shaft, a second slide carrying said first mentioned slide and also capable of movement in a horizontal plane transversely of said machine, a carrier for said slides, means for moving said carrier longitudinally of said machine, a 65 crank motion for moving said slides trans- 70 versely of the carrier to bring said grinding wheel into grinding engagement with the workpiece, means for dressing said wheel, and means for moving said first mentioned slide a predetermined distance relatively to said second mentioned slide during movement of said carrier away from said headstock to compensate for wear on said grinding wheel and its reduction in diameter by dressing.

7. A raceway grinding machine comprising a headstock capable of oscillation about a vertical axis and including a horizontally dis- 75 posed rotatable shaft to which the workpiece is adapted to be secured, a horizontally dis- 80 posed rotatable grinding wheel shaft, means for moving said shaft longitudinally of the machine to carry the grinding wheel into and out of the workpiece, a crank motion for moving said shaft transversely of said machine to cause a grinding wheel mounted thereon to move into grinding engagement with said workpiece, means for dressing said wheel, and means for moving said shaft transversely of the machine as the grinding wheel is being moved away from the work to compensate 85 for wear on the grinding wheel and its reduction in diameter by dressing.

8. A raceway grinding machine of the class described comprising a horizontally dis- 90 posed grinding wheel shaft, a slide upon which said shaft is mounted, a second slide upon which said first mentioned slide is mounted, a carrier upon which both said slides are mounted, said carrier being mov- 95 able longitudinally of the machine for the purpose of moving said grinding wheel into and out of the workpiece, actuating means including a crank for moving said slides together transversely of the machine to cause the grinding wheel to engage the workpiece, means for dressing said wheel and means for moving said first mentioned slide a predetermined distance transversely of the machine relatively to said second mentioned slide to 100 compensate for wear of the grinding wheel and its reduction in diameter by dressing.

9. A raceway grinding machine of the class described comprising a horizontally dis- 105 posed rotatable grinding wheel shaft, a slide upon which said shaft is mounted, a second slide upon which said first mentioned slide is mounted, a carrier upon which both said slides are mounted, said carrier being mov- 110 able longitudinally of the machine to carry the grinding wheel into and out of the work- 115 piece, actuating means including a crank for moving said slides together transversely of the machine to move the grinding wheel into and out of engagement with the work, a shaft journaled in said first mentioned slide and having tooth-like projections co-operating with a nut-like element associated with said second mentioned slide, a ratchet wheel mounted upon said shaft, a pawl rockably 120

125

mounted upon said shaft for engagement with said wheel, a finger associated with said pawl, and a cam-like surface mounted upon the frame of the machine, said finger riding upon said surface to cause rotation of said ratchet wheel and movement of said first-mentioned slide relatively to said second mentioned slide when the carrier is moved longitudinally of said machine.

10 10. A raceway grinding machine of the class described comprising a horizontally disposed grinding wheel shaft, a slide upon which said shaft is mounted, a second slide upon which said first mentioned slide is mounted, a carrier upon which both said slides are mounted, said carrier being movable longitudinally of the machine to carry the grinding wheel into and out of the workpiece, actuating means including a crank for 15 moving said slides together transversely of the machine to bring the grinding wheel into and out of grinding engagement with the work, means for moving a dressing device into position to engage the peripheral surface of said wheel on that movement of said carrier that carries the grinding wheel out of the workpiece, and means for moving said first-mentioned slide a predetermined distance transversely of the machine relative to 20 said second-mentioned slide, to compensate for wear of the grinding wheel and its reduction in diameter by dressing.

11. A raceway grinding machine of the class described, comprising a headstock for a workpiece, a rotatable shaft for a grinding wheel, a carrier for moving said shaft longitudinally of the machine to carry a grinding wheel mounted thereon into and out of the workpiece, means for moving said shaft 25 transversely of the machine to move said grinding wheel into grinding engagement with the workpiece, an oscillatable truing device pivotally mounted upon said carrier, a pin projecting from the frame of the machine, a bell crank lever pivotally mounted upon said carrier, said lever co-operating with said pin during movement of said carrier longitudinally of the machine to bring said truing device into and out of position to 30 operate upon the peripheral surface of said grinding wheel and means operative on the longitudinal movement of said wheel away from the workpiece for transversely shifting its shaft a predetermined distance to compensate for wear on the grinding wheel and its 35 reduction in diameter by said truing device.

12. A grinding machine of the kind described comprising an oscillatable headstock for a workpiece, a rotatable shaft for a grinding wheel, means for moving said shaft endwise to dispose the wheel within the workpiece, and crank means, operating in timed relation to the oscillation of the headstock, to move said shaft transversely, thereby to 40 carry said grinding wheel into and out of

grinding engagement with said workpiece. In testimony whereof I have signed my name to this specification.
